UNITED STATES PATENT OFFICE.

HUGO F. LOEPERE, OF BUFFALO, NEW YORK, ASSIGNOR OF ONE-HALF TO
ZELMIR L. H. LOEPERE, OF SAME PLACE.

FUMIGATOR.

SPECIFICATION forming part of Letters Patent No. 473,631, dated April 26, 1892.

Application filed March 19, 1891. Serial No. 385,635. (No model.)

To all whom it may concern:

Be it known that I, HUGO F. LOEPERE, a citizen of the United States, residing at Buffalo, in the county of Erie and State of New York, 5 have invented new and useful Improvements in Fumigating Apparatus, of which the following is a specification.

This invention relates to a device which is more particularly designed for fumigating 10 potted plants, but which may be used for fumigating other articles.

The object of my invention is to produce a simple and inexpensive fumigating apparatus for domestic and other purposes, by which 15 the fumes are conducted to the plants in a very efficient manner, and which can be readily converted into a table when not in use and which can be compactly folded for transportation.

20 In the accompanying drawings, Figure 1 is a perspective view of my improved fumigating apparatus, showing the cover partly folded back to expose the interior. Fig. 2 is a vertical transverse section showing the parts in 25 position for use. Fig. 3 is a similar view showing the cover-frame depressed and the apparatus converted into a table.

Like letters of reference refer to like parts in the several figures.

30 A represents the open rectangular main frame, composed of four side boards *a* and corner-blocks *B*, secured in the inside corners of the main frame.

35 C represents the legs which support the main frame. Each of these legs is provided at its upper end with an externally-screw-threaded portion *d*, which engages in a screw-threaded socket *e*, formed in the lower end of the corner-block *B*.

40 D represents a grating secured horizontally inside of the main frame for supporting the flowers, plants, or other articles to be fumigated. This grating consists, preferably, of wire-cloth of coarse mesh and is secured to 45 the main frame near the lower edge thereof in any suitable manner.

F represents a skeleton frame, which supports a flexible cover *f*. This cover-frame *F* consists, preferably, of four bars or rods *g*, 50 connected at their ends and forming a rect-

angular frame of about the same size as the main frame.

h represents upright rods, which support the frame *F*. These rods are arranged to slide vertically with their lower portions in a passage *i*, formed in each of the blocks and the leg attached thereto. The upper end of each sliding rod *h* is provided with an eye *i'*, by which it is pivotally attached to one of the rods of the cover-frame *F*. The latter can 55 be adjusted vertically to suit the height of the plants or other articles to be fumigated by sliding the rods *h* in the openings *i*. After the frame has been adjusted it is secured in place by thumb-screws *j*, arranged in the 60 corner-blocks and bearing against the supporting-rods. The flexible cover *f* extends over the skeleton frame *F* and hangs with its 65 end and side portions along the four sides of the main frame, thereby forming with the 70 main frame a fumigating-chamber having a closed top and sides and an open bottom.

K represents a fumigating pot or stove in which fumes of tobacco or some other fumigant are generated. This fumigating-pot is 75 placed underneath the grating of the fumigating-chamber, so that the rising fumes will come in contact with the plants or other articles to be fumigated.

In fumigating plants or flowers, as heretofore practiced, the fumes approached the plants from the top and the insects on the plants would seek refuge in the crevices on the under side of the leaves, which form small air-pockets into which the fumes do not enter. 85 By constructing the fumigator so that fumes approach the plants from below the rising fumes come first in contact with the under sides of the leaves and flowers, which causes the insects to seek refuge on the upper side of 90 the leaves and flowers; but the fumes in continuing to rise soon envelop the entire plant and destroy the insects.

When the fumigator is not in use, it can be readily converted into a table by folding the 95 flexible covering and placing it upon the grate, lowering the cover-frame so that it rests upon the corner-blocks, and placing a table-top *L* upon the main frame, as represented in Fig. 3. This table-top may be provided with cleats 100

l, which fit against the sides and ends of the main frame and hold the table-top against displacement on the latter, whereby the fumigator can be utilized as an ordinary table.

5 When it is desired to ship the fumigator, the sliding rods of the cover-frame are removed from the hollow legs and folded against the side bars of the supporting-frame, while the legs are detached from their sockets and 10 placed upon the grating on the inside of the main frame, thereby packing the parts compactly and permitting the apparatus to be conveniently transported.

I claim as my invention—

15 1. The combination, with the main frame and the grating arranged in said frame, of a cover-supporting frame arranged on the main frame, and a flexible cover inclosing the top and sides of said frames and forming a fumigating-chamber having an open bottom, substantially as set forth.

20 2. The combination, with the main frame and the grating arranged in said frame, of a cover-supporting frame made vertically adjustable on the main frame, and a flexible cover extending across the top and sides of the cover-frame, substantially as set forth.

25 3. The combination, with the main frame and the grating arranged in said frame, of a 30 horizontal cover-supporting frame having vertical rods adjustably arranged in the main

frame, and a flexible cover resting on said supporting-frame, substantially as set forth.

4. The combination, with the main frame and the grating arranged in said frame, of a 35 horizontal cover-supporting frame, vertical rods pivoted with their upper ends to the supporting-frame and adjustably arranged with their lower ends in the main frame, and a flexible cover resting on the supporting-frame, 40 substantially as set forth.

45 5. The combination, with the main frame and the grating arranged in said frame, of a horizontal cover-supporting frame, blocks secured to the inner side of the main frame and provided with screw-threaded sockets, legs provided with screw-threaded ends engaging in said sockets, vertical rods pivotally secured with their upper ends to the supporting-frame and adjustably arranged with their 50 lower ends in the openings in the blocks and legs, thumb-screws arranged in said blocks and bearing against the vertical rods, and a flexible cover resting upon the supporting-frame, substantially as set forth. 55

Witness my hand this 13th day of March, 1891.

HUGO F. LOEPERE.
